UNITED STATES PATENT OFFICE

LAWRENCE I. CARMER, OF MATAWAN, NEW JERSEY

BURIAL VAULT

Application filed April 21, 1928. Serial No. 271,767.

This invention relates to improvements in burial vaults, preferably of wire netting and cement or other plastic material and method of automatically sealing same, and has for its object the provision of vault simple in construction, relatively light in weight and at the same time durable in strength and which can be produced at a minimum cost.

A further object is to provide a burial vault 10 air and water tight when closed and one which is substantially self-sealing.

A still further object is to provide a vault which can be closed and sealed without the necessity of one going down into the grave 15 for that specific purpose, but can be manipulated from the surface of the ground by means of suitable handles and other facilities.

A still further object is to provide a supporting means, the top of which lies in the 20 same plane with top edge of main body of vault, for the lid preparatory to being put into place on the vault.

With this and other objects in view the present invention consists in the combination, arrangement of parts and the method of manipulating same, as will be hereinafter more fully described, shown in the accompanying drawings, and particularly pointed out in the appended claims, it, of course, being understood that minor changes as to details may be made without departing from the spirit of the invention. The reference characters of this description are applied to the corresponding parts in the several views 35 in which—

Figure 1 is a perspective view of vault having part of cover broken away.

Figure 2 is a sectional view through grave showing vault in place, with parts broken 40 away, showing casket.

Figure 3 is a fragmentary view of grave showing parts of vault, and of cover, resting on support.

Figure 4 is a side elevation of vault with 45 parts broken away.

Figure 5 is a transverse section of vault taken on line 5—5, Figure 4.

Figure 6 is a fragmentary view of reinforcing wire-netting basket.

Figure 7 is a modified form of reinforce-

ment, in which the material consists of flat bars riveted together.

Referring to the drawing, in details, 12 is the vault, which, when in use is placed in a grave 13 as shown at 14. 15 is the main body portion of vault, having a cover portion 16. The main body consists of a bottom or horizontal portion and four vertical walls, and is substantially rectangular in shape. Within the edges of side and end walls is a continuous groove 17 around the vault, and in cross section describes an arc of a circle.

The cover member 16 has broad, flat side and end edges and is substantially rectangular in plan, with arched top as at 18, and is provided on its under side, near and parallel to its outer edges, with a depending portion, or tongue, 19 which is engaged by groove 17, but whose radius of its arc is less than that of 17.

At 20 is shown portions of the reinforcing net wire basket embedded within the cement, or other material used, 21 is reinforcement in cover, 22 is metal handle bars in cover, which extend beneath the reinforcement and which are further reinforced by transverse steel bands 23 extending between opposite handles. The handles are provided with straps, cables, or other suitable means, as shown at 24 for the convenient handling of the cover from the surface of the ground dispensing with the necessity of entering the grave to adjust, or cement, the cover.

The vault 12 having been positioned within the grave, dirt, sand, or other suitable material 25 is placed around, and between, the vault and wall of grave as at 26 and 27. On one side at 27, the filling-in material is capped with blocks 28 and boards 29 so as to provide a substantial support for cover 16 and to equally distribute its weight over entire surface of supporting means. 30 is cementing material placed in groove and on upper edges of side and end walls which seals vault air and water tight when cover is in place as at 31, Figures 4 and 5.

Prior to placing cover on vault it is lowered into the grave edgewise and rests on supporting means or, boards 29, at an angle of approximately 90 degrees with the plane of the 100

surface to be covered, as shown at 32, Figures 2 and 3. The point 34 Figure 3 becomes a pivotal point, or axis, around which the cover moves while being rotated into its final position, which is accomplished by exerting an upward pull on straps 24 until the center of gravity of cover passes outside of its footing, or bearing, then gradually decrease the tension in the strap 24 and the convex surface of tongue 19 and concave surface of groove 17 will mesh as cogs of a gear wheel and guide the cover accurately into position. The weight of cover is sufficient to force the green cement into the minutest crevices and insure a perfect air and water tight joint, or bond.

Having thus described my invention what I claim and desire to protect by Letters Patent is:

- 20 1. Means for effecting a closure of burial vaults from a point outside the grave in which the vault is placed, comprising a cover formed to be held in closing position with respect to a vault by its own weight and having a relatively broad, flat side edge upon which it rests in substantially upright position when open, a support for the cover in its open position arranged in the grave adjacent one side of the vault and substantially flush with the top edge thereof, said cover resting with its broad side edge on the support to tilt over to a closing position with respect to the vault, and means operable from without the grave and detachably connected with the cover adjacent each of the side edges thereof to tilt said cover and sustain the same in its movement from an open position resting on the support to a closing position on the vault.
- 40 2. Means for effecting a closure of burial vaults from a point outside the grave in which the vault is placed, comprising a relatively massive cover having at least one relatively broad, flat side edge upon which the cover rests in a substantially upright position when open, a removable support for the cover in its open position arranged in the grave adjacent one side of the vault and parallel thereto and substantially flush with the top edge thereof, said cover resting with its broad side edge on the support to tilt over to a closing position with respect to the vault, and means including straps reaching to a point without the grave and detachably connected with the cover adjacent each of the side edges thereof to tilt said cover and sustain the same in its movement from an open position resting on the support to a closing position on the vault.
- 60 Signed at Matawan, in the county of Monmouth and State of New Jersey this 27th day of March, A. D. 1928.

LAWRENCE I. CARMER.
